UNITED STATES PATENT OFFICE.

HARRY LEVI, OF PHILADELPHIA, PENNSYLVANIA.

GO-CART.

SPECIFICATION forming part of Letters Patent No. 680,049, dated August 6, 1901.

Application filed September 19, 1900. Serial No. 30,454. (No model.)

To all whom it may concern:

Be it known that I, HARRY LEVI, a citizen of the United States, residing in the city and county of Philadelphia, State of Pennsylvania, have invented a new and useful Improvement 5 in Go-Carts, of which the following is a specification.

My invention consists of an improvement in go-carts having means whereby the back 10 and foot pieces can be moved simultaneously or can be moved independently of each other.

It further consists of novel details of construction, all as will be hereinafter set forth.

Figure 1 represents a vertical sectional 15 view of a go-cart embodying my invention. Fig. 2 represents a perspective view of a portion of the mechanism on an enlarged scale. Fig. 3 represents a perspective view of a detailed portion of the mechanism. Fig. 4 represents a sectional view on line αx , Fig. 2.

Similar letters of reference indicate corresponding parts in the figures.

Referring to the drawings, A designates a go-cart, the same having the body portion B 25 and the running-gear C, which is of usual construction, and hence it is not necessary to further describe the same.

D designates the back piece, which is pivoted in the base E of the body portion B, and 30 F designates the footpiece, which is pivoted to the body portion in the extensions G.

Secured to the running-gear of the go-cart 35 is a bar H, having openings J therein at intervals, and mounted upon said bar is a runner or carrier K, having the opening L in one side thereof and having pivotally attached thereto the link M, the other end of said link being movably secured to the footpiece F.

N designates a runner or carrier which is 40 also mounted upon the bar H, said carrier being provided with openings P and having on its lower end a sleeve Q. Mounted in said sleeve is a rod R, having on its end adjacent the sleeve Q a pin S, which is on one side of 45 said carrier N, said rod also carrying a hook T, which is on the other side of said carrier, said hook being provided with a shoulder U, against which one end of a spring V is adapted to bear, the other end being suitably secured 50 to the carrier N. The opposite end of said rod R is mounted in a sleeve W, which is supported by a bar A', connected with the back

piece D. The end of the rod carried by the sleeve W has attached thereto an eye or hook B', which is connected with the rod C', the latter being connected by a lever D' to a rod E', which is adapted to be locked to the back piece. A stop F' is provided on the eye B' and a stop G' is attached to the bar H to prevent improper movement of the carrier N. 60

The operation is as follows: The parts being in the position seen in full lines in Fig. 1, the pin S is in engagement with the openings P in the carrier N and with one of the openings J in the bar H and the parts are 65 locked. In order to change the position of the back and foot pieces, the rod E' is depressed and C' is raised, which carries with it the eye B', and thus revolves the rod R in the sleeves W and Q. In turning, the rod R carries with 70 it the pin S, which is thus removed from the opening P in the carrier N and from the opening J, with which it is in engagement. By pulling back the back piece D the carrier N will now slide upon the bar H, pushing the carrier 75 K before it, and thus the back piece D can be lowered until the carrier N has moved its full extent on the bar H. If now it is desired to return the parts to the position seen in full lines in Fig. 1, the rod E' is depressed and the 80 rod C' is raised until the hook T engages with the walls of the opening L in the carrier K, the pin S again being released or withdrawn from the opening P in the carrier N and from the opening J, with which it is engaged, and by 85 pushing up the back piece the parts will again be in the position seen in full lines, Fig. 1. When it is desired to change the position of the back piece D without moving the footpiece F, it being understood that the parts 90 are at their farthest extent on the bar H, the back piece D is raised, carrying with it the rod R to such a point that the hook T cannot engage with the wall of the opening L and carrier K. Should the pin S engage with any 95 of the openings J on the bar, it will readily be seen that by depressing the rod E', which elevates the rod C', said pin can be disengaged from the said opening J without the said hook T engaging the carrier K and the back piece 100 moved up into any position desired—as, for example, to the position seen in full lines in Fig. 1.

Having thus described my invention, what

I claim as new, and desire to secure by Letters Patent, is—

1. In a go-cart, a body portion, a back piece and a front piece pivoted to said body portion, separate runners connected with the front and back piece respectively, means on which said runners are adapted to travel and means for coupling and uncoupling said runners.
2. In a go-cart, a body portion, a front piece, and a back piece pivoted thereto, a runner connected with said back piece, a bar upon which said runner is mounted, a runner connected with the footpiece and mounted on the same bar, and means for operating said runners in unison.
3. In a go-cart, a body portion, a footpiece, and a back piece pivoted thereto, a runner connected with said back piece, a runner connected with said footpiece, a bar upon which said runners are mounted, means for moving said carriers in unison, and means whereby said runners can be operated separately.
4. In a go-cart, a body portion, a back piece, a footpiece, a bar suitably supported and having openings therein, a runner connected with said back piece and mounted on said bar, a runner connected with said footpiece and mounted on said bar, a rod movably connected with said first-mentioned runner, a pin on said rod adapted to pass through openings in said first-mentioned runner and said openings in said bar, and a hook on said rod adapted to engage with the second-mentioned runner in order to move the same.

5. In a go-cart, a body portion, a back piece, a footpiece pivoted thereto, a bar suitably supported and having openings therein, a runner mounted on said bar, a rod having one end mounted in a sleeve on said runner, the other end mounted on a sleeve supported by said back piece, a pin on said rod adapted to pass through openings in said runner and through the openings in said bar, means for revolving said rod, a second runner mounted on said bar and connected with said footpiece, and a hook on said bar adapted to engage with an opening in said second runner.

6. In a go-cart, a body portion, a front piece and a back piece pivoted to said body portion, a runner connected with said back piece, a runner connected with said front piece, means for supporting said runners on which they are adapted to travel, means for operating said runners in unison or separately, and means for coupling and uncoupling one of said runners with said supporting means.

7. In a go-cart, a body portion, a back piece and a front piece pivoted to said body portion, a runner connected to said front piece, a runner connected with said back piece, means on which said runners are adapted to travel and means on said second-mentioned runner for connecting and disconnecting the same with respect to said first-mentioned runner.

HARRY LEVI.
